UNITED STATES PATENT OFFICE.

CHARLES E. BEDAUX, OF CLEVELAND, OHIO.

GAME APPARATUS.

Application filed April 14, 1922. Serial No. 552,702.

To all whom it may concern:

Be it known that I, CHARLES E. BEDAUX, a citizen of the United States, residing at Cleveland, in the county of Cuyahoga and 5 State of Ohio, have invented new and useful Improvements in Game Apparatus, of which the following is a specification.

The present invention relates to game apparatus; and its object is to provide apparatus whereby a game requiring skill may 10 be played.

This object is attained by, and the invention finds preferable embodiment in, the game apparatus hereinafter particularly described in the body of this specification and 15 illustrated by the accompanying drawings, in which:—

Figure 1 is a view of game apparatus partly in plan and partly in longitudinal 20 section taken on a horizontal plane corresponding to line 1—1 of Figure 2;

Figure 2 is a longitudinal sectional view of the same, the table portion thereof being sectioned on a vertical plane corresponding 25 to line 2—2 of Figure 1 and the parts above the table portion being sectioned on a vertical plane corresponding to line II—II of Figure 1;

Figure 3 is a transverse sectional view of 30 parts of the same taken on a vertical plane corresponding to line 3—3 of Figures 1 and 2;

Figure 4 is a like view of parts of the same taken on a vertical plane corresponding 35 to line 4—4 of Figures 1 and 2;

Figure 5 is a sectional enlarged view of certain parts taken on vertical planes corresponding to line 5—5 of Figure 1; and

Figure 6 is a top plan enlarged view of 40 certain parts.

In the embodiment of the invention chosen for illustration by the drawings and for detailed description in the body of this specification, my game apparatus comprises 45 a horizontally disposed table portion 1 preferably about twelve feet long (in the longitudinal direction of Figures 1 and 2) and wide enough (transversely to said direction) to accommodate the apparatus to a number 50 of players, as for instance twelve players, in which case the table is preferably about twelve feet wide. Adjacent one end of the table is positioned the principal part of the 55 several mechanisms whereby the game is played on the table, one such mechanism being provided for each player, such plurality

of like mechanisms being disposed side by side, only one of the several mechanisms however being illustrated. Each of said several mechanisms comprises: A projector 2, for 60 projecting the projectile 3 along the table's surface toward the right hand side of Figures 1 and 2, is horizontally-slidably carried by its rods 4 (four rods being shown) slidably bearing in tubular guides 5 fixed in 65 the rear wall 6 of the stall or box 7 supported on the table. Coiled springs 8 surrounding these guides and rods serve to urge the projector in its operative movement. A plate 9 is freely slidably mounted on these 70 guides 5 between the springs 8 and means for increasingly tensioning such springs, said means comprising a member 19 having an arm 10 (or plurality of such arms angularly disposed as shown) turnably mounted 75 on a spindle 11 and having a lug 12, and an element—the pulley 13—turnably mounted on said spindle and having a lug 14 adapted by the turning of said element to engage the lug 12 and thus turn with it the 80 member 19 and its arm 10. This pulley 13 may be turned by suitable means as by the pulley 15, which with the pulley 13 carries a belt 16, the pulley 15 being on the long 85 shaft 17 extending to the front end of the table—the right hand side of Figures 1 and 2—where it may be rotated by its crank wheel 18.

In playing the game, the players stand at the front end of the table—the right hand side of Figures 1 and 2—and the attendant stands at the opposite end, behind the stalls or boxes 7. The attendant draws the projectors of the several mechanisms toward him as by their handles 20 extending 90 through slots 21 in the sides 22 of the respective stalls or boxes, until the projectors are held by their keepers 23 engaging the upwardly spring-pressed catches 24. The projectiles 3 preferably in the form of 100 horses and jockeys mounted thereon as shown are placed in the stalls respectively and the doors 25 thereof are closed. Each player now turns the shaft 17 which through the lug 14 of the element 13 engaging the lug 12 of the member 19 turns said member, an arm 10 thereof pressing by its friction roll 26 against the rear side of the plate 9 thus increasingly tensioning the 105 springs 8 against the projector held by the catch 24. It is evident that as soon as the arm's roll 26 passes a horizontal line ex-

tending through the axis of the member 19, the compressed springs will quickly press the plate 9 rearwardly thus releasing the tension of the springs. For the purpose 5 hereinafter explained, the object of each player is to tension the springs 8 to the utmost degree of their compression predetermined by the limit of approach of the plate 9 to the projector 2 and to stop short of 10 turning the arm 10 beyond said horizontal line. The attendant now unlocks the doors 25 permitting them to open, by raising the handle 28 of the lever 29 whose inner end is connected to the catch 30, and thereupon 15 at a given signal each player draws the rod or cord 31 to release the catch 24 from the keeper 23 of the projector, which thus released is sprung forward by the springs 8 and projects the projectile toward the players, that projectile which is thrown furthest winning the game or play. It will be seen that that player, the springs 8 of whose 20 playing mechanism are under the greatest degree of tension prior to his drawing his 25 rod or cord 31, wins the play.

Gearing may manifestly be interposed between the two portions 17¹ and 17² of the shaft 17 so that when the hand wheel portion 17¹ of the shaft turns about six times 30 the rear portion 17² of the shaft turns only once.

The projectile 3 may be moved rearwardly against the projector when held by its catch 24, as by the rod 35 having a portion 35 extending through the slot 37 in the table and adapted to engage the projectile, said rod being slidable along a guide 38 below the table and being adapted to be raised through said slot in its operative movement. 40 Springs 50 throw open the doors 25 when the catch 30 is released.

The invention being intended to be pointed out in the claims, is not to be limited to or by details of construction of the particular 45 embodiment thereof illustrated by the drawings or hereinbefore described.

I claim:

1. In game apparatus; a projectile; a 50 projector therefor releasably held against operative movement; a spring pressing the projector in its operative movement; a turnably mounted arm adapted to be turned to increasingly tension the spring and freely

turnable by the spring to release the same from a predetermined tension; a turnably 55 mounted element adapted to engage the arm and turn the same in its spring-tensioning movement.

2. In game apparatus; a projectile; a projector therefor releasably held against operative movement; a spring pressing the projector in its operative movement; a turnably mounted arm having a lug and adapted to be turned to increasingly tension the 60 spring and being freely turnable by the 65 spring to release the same from predetermined tension; an element turnably mounted concentrically with the arm and having a lug adapted to engage the arm's lug to turn the arm in its spring-tensioning move- 70 ment.

3. In game apparatus; a table; a projectile; a projector therefor; a catch for releasably holding the projector against operative movement; means for releasing the 75 catch; a freely slideable plate; a spring intermediate the projector and the plate and tensioned by their approaching movement; a turnably mounted arm having a lug and adapted to be turned to abut the plate and 80 move it in spring-tensioning direction and being freely turnable to release the spring from a predetermined tension; an element turnably mounted concentrically with the arm and having a lug adapted to engage the 85 arm's lug to turn the arm in its spring-tensioning movement.

4. In game apparatus; a table having a slot; a projectile; a longitudinally movable rod having a portion extending through 90 said slot adapted to engage the projectile to move the same; a projector for the projectile releasably held against operative movement; a spring pressing the projector in its operative movement; means for in- 95 creasingly tensioning the spring and for releasing the same from a predetermined tension.

In testimony whereof I have hereunto set my hand at New York, N. Y., this 6th day 100 of April, 1922.

CHARLES E. BEDAUX.
